UNITED STATES PATENT OFFICE.

JOHN A. GEER, OF COLCHESTER, CONNECTICUT.

MACHINE FOR MAKING CORDAGE.

SPECIFICATION forming part of Letters Patent No. 248,446, dated October 18, 1881.

Application filed April 4, 1881. (No model.)

To all whom it may concern:

Be it known that I, JOHN A. GEER, of Colchester, New London county, in the State of Connecticut, have invented new and useful Improvements in Machines for Making Cordage; and I do hereby declare that the following is a full and correct description of the same.

By means of an expansive score-pulley my machine becomes capable of making several different sizes of cord. The strands are laid up in a vertical hollow spindle, and I am thereby enabled to reel it off from the bottom of said spindle without occupying more room than is required to receive the reel. All the separate spindles are driven by a single band, and therefore a uniform drag on the strand is obtained without liability to slip.

That others may fully understand my invention, I will particularly describe it, having reference to the accompanying drawings, where-

in—
Figure 1 is a perspective view of my machine. Fig. 2 is a vertical central section of the same. Fig. 3 is a plan view of the same. Fig. 4 is a perspective view of the expansive pulleys. Fig. 5 is a vertical central section of the same.

The frame of my machine consists of two horizontal spiders, A, bolted to a bracket, B, which is attached rigidly to some solid support. A hollow spindle, C, passes through the centers of the two spiders and has its bearings therein. At the corresponding extremities of the arms of the spiders A there are bearings for the spindles D D D, and a leader-arm, E, projects from the spindle C horizontally below the lower spider to lead the completed cord and lay it on the reel F, which is mounted and is capable of rotation upon an independent bracket or support below the lower spider A. Each spindle D passes up through its bearing in the upper spider, and is provided at its top with a pulley, G. The upper end of each spindle D is also made with a hollow center, and said hollow penetrates to a point below the upper bearing, where it has a lateral orifice, a, in the side of the spindle.

Near the bottom of each spindle D there is a platform, H, provided with a number of vertical spool-pins, I—say five—though the number may be greater or less, and there is also

on the side of each spindle a guide-eye, J. The spools of thread K are placed on the spool-pins I, an equal number of spools upon each platform H. The thread from each spool is passed through the guide-eye J of its spindle, and is then wound one or more times around the spindle, to secure a proper frictional tension, and is then passed in at the orifice a and out through the hollow center. The several threads thus grouped constitute one strand of the final cord.

A score-pulley, L, is rigidly secured to the spindle C above its upper bearing, and at the extreme upper end of said spindle there is a head, M, with bearings for a transverse feed-roller, N, which is driven by a bevel-gear, b, at the one extremity of its shaft, and said gear b is, in its turn, driven by a similar gear, b', mounted on a score-pulley, O, which is located immediately above the pulley L, and turns upon the spindle C as an axis.

Above the head M there is a center piece, P, supported on a pillar, Q, and from said center piece; three leader-arms, d, extend outward and downward, terminating just above the hollow ends of the spindles D; and immediately below the center piece, P, there is a clamp-tension, R, to regulate and make the twist or lay uniform.

The above are the mechanical features of the machine.

The several strands from the hollow spindles D are led up the respective arms d and brought together in the center piece, P, and thence they pass down together through the clamp R into the head M and several times around the feed-roller N, and thence down through the tubular spindle C, and outward over the end of the leader-arm E to the reel F. The whole is driven by a single belt, S, which is actuated by any convenient or proper motor. The belt S comes to the machine (in the direction of its movement, as shown by the arrows,) and passes first around the pulley L rather more than half-way, and it thence passes over the pulleys G in successive order, and returns to the pulley O, around which it passes rather more than half and leaves the machine toward the prime-mover pulley. By this arrangement all of the rotating parts receive motion from the same belt, and necessarily the several movements are, as nearly as pos-

sible, synchronous. The rotation of the pulley G and spindle D carry the several spools around the axis of said spindle, so that between its extremity and the leader-arm *d* the several threads are twisted around each other or laid up in a strand, and in that condition the strands pass down through the clamp R to the head M and feed-roll N, the horizontal rotation whereof is in a direction opposite to the rotation of the spindles D, so that the several strands are twisted together between the feed-roll N and the clamp R.

The head M and the pulleys L and O all revolve in the same direction; but the pulley O being of less diameter than the pulley L, it revolves with a greater speed, and the motion of said pulley O with reference to the head M, with the feed-roller and its driving-gear *b*, is therefore differential, the rapidity of the rotation of said feed-roller being dependent upon and in proportion to the difference in rotative velocity of said pulleys L and O. The velocity of feed with reference to rapidity of rotation of the spindle C will determine the lay or hardness of the twist, and incidentally the size of the cord made upon the machine may be varied, because a small cord will require more turns or twists to a certain length of feed than will a larger cord. Therefore by varying the relative diameters of the pulleys L and O the lay may be varied or the machine adapted to cords of various sizes. To facilitate the adjustment of these relations I have made the pulleys L and O expansible, as shown in Figs. 4 and 5, so that the diameters of their pitch-lines may be varied at will, and without the dismemberment of the machine. This result I accomplish by making the pulley in two parts, divided horizontally through the groove, and provide each part with teeth *e*, the faces whereof are beveled backward in the plane of the groove-face, but interlocking laterally with each other, so that while said parts are in engagement with each other at all, there will still remain a groove for the belt, but the diameter of the pitch-line of said groove will be expanded as said parts are brought together, causing the groove-faces to intersect farther from the center, and vice versa. They may be held in adjustment by a set-screw, *s*, or by some other suitable means.

The reel F is provided with a friction-brake, T, or other means of retarding its rotation, so as to cause the cord to be laid upon it with any desired degree of tightness.

Having described my invention, what I claim as new is—

1. A series of revolving spool-platforms, whereby the threads are twisted to form strands, combined with a revolving tubular spindle and feed-roller mounted thereon, with means for operating the same, and pulleys G L and belt S, whereby the thread-twisters and the strand-twister may be actuated by the same belt, substantially as set forth.

2. A series of revolving spindles of which each one carries a platform adapted to support a set of spools, and means for operating the same, so that the several threads to form a strand are taken from the spools on said stands and twisted together, and a series of leader-arms combined with a tubular spindle and means for operating the same, whereby the strands are laid, a feed mechanism, and an arm, E, attached to and revolving with said spindle, and a reel whereon said arm deposits the finished cord.

3. A series of revolving tubular spindles each provided with a platform adapted to carry a set of spools, a tubular center spindle, and devices, whereby the cord is fed and delivered, combined with an actuating belt and pulleys to drive the several parts, arranged to be all actuated directly but independently by said belt, substantially as set forth.

4. A series of spool-stands and a twisting-spindle, whereby the threads are twisted to form strands and the strands are twisted to form the cord, a feeding device, and a revolving arm, whereby the cord is delivered, combined with an independent winding-reel and a tension-brake for said reel, whereby its rotation is retarded, as set forth.

5. A revolving twisting-spindle, a feed-roller mounted transversely thereon, and a driving-pulley connected to said spindle, combined with a variable differential pulley connected with and actuating said feed-roller, whereby the hardness of the lay may be varied or the machine caused to make cords of various sizes.

6. A tubular twisting-spindle, a series of rotating spool-spindles, a series of leader-arms, whereby the twisted thread-strands are conducted into the end of the tubular twisting-spindle, a feeding device, a delivery-arm, and means whereby said moving parts are actuated, combined with a reel the axis whereof is coincident with the axis of said twisting-spindle.

7. The twisting-spindle C, transverse feed-roller N, and gears *b* and *b'*, combined with the pulleys L O, whereby the speed of the feed with relation to the speed of the twister may be made differential, as set forth.

8. A feeding and twisting mechanism consisting of the tubular spindle C and feed device mounted upon and revolving with said spindle to twist the cord, but capable of an independent feed movement combined, with expansible pulleys L O, as described, and suitable devices to connect said pulleys with the spindle and feed respectively, whereby the hardness of twist and lay may be regulated, as set forth.

JOHN A. GEER.
